UNITED STATES PATENT OFFICE.

MARTIN A. DILLEY, OF WASEPI, MICHIGAN.

RAILROAD-SIGNAL.

SPECIFICATION forming part of Letters Patent No. 424,051, dated March 25, 1890.

Application filed July 5, 1889. Serial No. 316,515. (No model.)

To all whom it may concern:

Be it known that I, MARTIN A. DILLEY, a citizen of the United States of America, residing at Wasepi, in the county of St. Joseph 5 and State of Michigan, have invented certain new and useful Improvements in Railroad-Signals, of which the following is a specification.

My invention has relation to railroad-signals of that class used to indicate "danger" or "safety" to approaching trains; and the object is to provide a signaling device carrying an indicating-lantern which can be readily removed and replaced without the usual 15 climbing to it by ladder or other means of reaching a signal placed at an altitude.

I accomplish the purpose of my invention by means of the mechanism and appliances illustrated in the accompanying drawings, 20 wherein—

Figure 1 is a front view in elevation. Fig. 2 is a side view of the same. Fig. 3 is a view of the lantern-frame on a larger scale than shown in the preceding figures. Fig. 4 is a 25 view of the lantern, showing the journals of different diameters. Fig. 5 is a side view of the lantern arranged in the frame, on larger scale, the apron being shown in dotted lines as lifted by the force of the wind. Fig. 6 is 30 a view showing the signal-staff tilted and the lantern in position to be removed. Fig. 7 is a vertical central section of the coupling and protecting-shield. Fig. 8 is a view of the coupling removed from its connection to the signal-staff.

It is designed to construct the parts of the apparatus of metal, using for the supports and staffs proper-sized pipe-iron.

A designates the base of the signal-frame, 40 composed of upper and lower metal plates 1 2, connected by corner bars 3, substantially as shown. The base-frame is set in the ground, and either has the ground firmly tamped about it or it may be set in masonry-work.

45 Arranged in the base are two vertical supports 4 5, fixed in position and extending up to such a height as may be desired. In the upper end of these supports is journaled a shaft 6, having a hole 7 arranged transversely 50 to its axis through the middle to take and hold the tilting signal-staff, as hereinafter specified. The supports 4 5 are suitably

braced by means of rods 8, having their upper ends secured to a cross-piece 9, arranged on the supports, and their lower ends carried to the corner bars 3 and properly secured thereto. On the upper plate 1, between the supports 4 and 5, is secured a bridge-tree 10, having a step-bearing in the middle to take the toe of the lower section 11 of the 60 staff. This section of the staff is projected through a bearing in a cross-piece 12, fixed on the supports, substantially as shown. The projecting part of this section of the staff is provided with oppositely-arranged studs 13 65 14 to engage similarly-arranged slots 22 in the coupling on the upper section of the staff. At the lower end of this section is a lever 15, to one end of which is fastened the cable or rod which runs to the lookout-house, and is 70 operated by a lever, as usual. The other end of the lever 15 is connected to an elbow-lever 16, fulcrumed on a support 17 on one of the vertical supports and carrying on its free arm a weight 18, made adjustable thereon. This 75 combination of levers is arranged so as to always throw the signal in a determined position and keep it there until moved by the party in charge.

B designates the upper section of the signal-staff, projected through the shaft 6 and carrying the coupling on its lower end and the lamp and semaphore on its upper end. The lower end of this section B is fixed in a sleeve 19, cored out at its lower portion to 85 readily admit the coupling.

21 designates the coupling-sleeve, cored out to slide on the staff and formed with side slots 22, extending part way through it to engage lugs 23 on the end of the staff. On the coupling are formed handles 24, by which the coupling may be turned to align with the lugs on the lower section of the staff if by any means the section should be turned out of alignment; or should the parts stick together they may be loosened by means of these handles. On the coupling and on the lower section of the staff, respectively, are staples 25 26, to which a lock may be attached to hold the parts together and from being separated by unauthorized persons. The coupling-sleeve slides on the staff and is supported thereon by the studs 23 lodging in the ends of the slots or grooves 22. By means of the

handles the coupling may be lifted from engagement with the lower section of the staff, and by the same means it may be directed and adjusted into engagement when the coupling is to be effected. On the lower part of the upper section of the staff is an adjustable weight 27 to balance the lamp and semaphore and prevent the too rapid descent of the lamp when the staff is tilted, also to render the return easy and certain. On the upper end of the staff is fixed a semaphore 28, above which is a seat-nut and a holding-nut, between which the foot of the lamp-frame support is held, substantially as shown. The support for the lantern-frame consists of a metal frame having a foot-piece 30, from which are projected two upright standards 31 32, bent forward at their upper ends, as seen at 33, so that the lantern will stand in proper position. At the upper end of the standards is a shaft 34, on which the lantern-frame is swung.

The lantern-frame consists of a metal frame 35, extending above and below the bearing-point and formed with bearings 36 37 in its lower end, one of which bearings, as 37, is made of larger diameter than the other to take the larger journal of the lamp. One of the arms of the lantern-frame is extended, as at 38, and has arranged thereon a counter-weight 39, which keeps the lantern-frame always in a vertical position. The lantern is provided with journals of different diameters formed to fit, respectively, the larger and smaller bearings in the frame, and this construction makes it impossible for the keeper to set the lamp in any other position in the frame than the right one, since it will only go in its bearings in that certain determined position. Across the upper arms of the lantern-frame is a shaft 40, on which is hung an apron 41, extending down and arranged to rest with its loose end on the shaft 34. The object and use of this apron is to act against the wind from one direction only—that is, coming from the direction against the lodged apron 41—so that the force of the wind on the apron, coming in the direction of the arrow, will have the greater force against the apron, which presents a larger area of resistance than the lamp, and thus keep the lamp in vertical position and from swinging outward. When the wind comes from an opposite direction to that indicated, the lantern is not disturbed, since the wind will swing the apron outward, as shown in Fig. 5 in dotted lines, and operate to seat the lantern more firmly in its position in the frame. To the staff above its shaft is pivoted a hand-rod *a*, which enables the operator to tilt the staff and return it to its vertical position.

The operation of my device is as follows: When the signal is held in position—as, for instance, broadside to the eye—by the weight at the base it displays a danger-signal. To place the signals in position signifying

“safety,” the lever 15 is moved by the operator, which gives the signal-staff a quarter-turn and places the semaphore in line to the eye, or this code might be reversed, as desired. At night the same movement turns the lantern to indicate the signals. To take the lamp down the coupling of the staff is lifted until disengaged. Then the hand-rod is grasped and the lower end of the upper section pushed backward, when the staff swings down until the lamp is readily reached by the hand and removed and the staff returned to its vertical position.

Having thus described my invention, what I claim, and desire to secure by Letters Patent, is—

1. In a railway-track signal, the combination of a lower section of signal-staff arranged to be turned on a vertical axis and formed with laterally-extended lugs at its upper end, an upper section of signal-staff mounted in a shaft or support and arranged to tilt therein and provided with a sleeve at its lower end, and a hollow coupling arranged to slide up and down in the sleeve and formed with grooves in the interior to engage the lugs on the lower section of the staff, substantially as described.

2. In a railway-track signal, the combination of a signal-staff composed of an upper and lower section detachably connected by a sliding coupling, and the upper section mounted to swing on a shaft supported by vertical supports constituting the supports of both sections of the signal-staff, substantially as described.

3. The combination, with the base-frame A and the vertical supports 4 5, of the vertical lower signal-staff section 11, supported in bearings and formed with laterally-extended studs 13 14, the upper signal-staff section B, journaled to the supports 4 5 and provided with the hollow sleeve 19, the sliding coupling 21, and the lantern journaled on the top of the staff, substantially as described.

4. The combination, with the tilting upper staff-section, of the lantern-frame formed with journal-bearings of different diameters and a lamp provided with journals of different diameters to fit the bearings, substantially as described, and for the purpose specified.

5. The combination, with a tilting signal-staff and a lamp-supporting frame, of a lamp-frame supported therein, said lamp-frame being extended above the bearings of the lamp, and an apron 41, swung to the top of the lamp-frame, substantially as described.

6. The combination, with a semaphore-staff provided with lamp-frame supports, of a lamp-frame pivoted in the supports and formed with lamp-bearings and extended above said bearings, an apron mounted to swing above the lamp, a lamp in the bearings, and a counter-weight on the lamp-frame, substantially as described.

7. The combination, with the upper and

tilting section and a lower and rotating section, of a sliding coupling formed with handles, staples on the coupling and the lower section, and a lock to engage the staples, substantially as described.

8. The combination, with the upper tilting staff and the lower section of the staff, of a hand-rod *a*, pivoted to the upper staff, sub-

stantially as described, and for the purpose specified.

In witness whereof I hereunto set my hand in the presence of two attesting witnesses.

MARTIN A. DILLEY.
